UNITED STATES PATENT OFFICE.

HOWARD PLYMALE, OF WEST HUNTINGTON, WEST VIRGINIA, ASSIGNOR OF ONE-HALF
TO IRA H. PINKERMAN, OF WEST HUNTINGTON, WEST VIRGINIA.

AUTOMATIC CIRCUIT-CLOSER.

1,205,259.

Specification of Letters Patent. Patented Nov. 21, 1916.

Application filed August 2, 1915. Serial No. 43,230.

To all whom it may concern:

Be it known that I, HOWARD PLYMALE, a citizen of the United States, residing at West Huntington, in the county of Cabell and State of West Virginia, have invented new and useful Improvements in Automatic Circuit-Closers, of which the following is a specification.

This invention relates to improvements in 10 automatic circuit closers and has particular application to a float controlled circuit closer for closing the circuits of electric motor driven pumps.

In carrying out the present invention, it 15 is my purpose to provide a float controlled circuit closer which will be found especially useful in connection with water reservoirs and the like and whereby the circuit of the motor connected with the supply pump will 20 be automatically closed when the water level in the tank drops below a certain point, thereby enabling the water to be pumped into the tank so as to maintain the water supply, and whereby the circuit of the pump 25 will be automatically broken when the level of the water in the reservoir rises to a pre-determined point, thereby preventing overflow.

It is also my purpose to provide an automatic circuit closer of the class described 30 which will embrace the desired features of simplicity, efficiency and durability, which will operate efficiently and effectively for its intended purpose and wherein the component parts will be so arranged and correlated 35 as to reduce the possibility of derangement to a minimum.

With the above and other objects in view, the invention consists in the construction, 40 combination and arrangement of parts hereinafter set forth in and falling within the scope of the claims.

In the accompanying drawing: Figure 1 is a diagrammatic view showing the circuit 45 connections between the circuit closer and the motor and the connection between the pump and the tank. Fig. 2 is an enlarged fragmentary longitudinal vertical sectional view through the reservoir and 50 circuit closer showing the float in the reservoir. Fig. 3 is a fragmentary vertical sectional view through the reservoir and circuit closer showing a modified arrangement.

Referring now to the drawing in detail, 1 55 designates a water pump of any suitable

construction having an inlet port and an outlet or discharge port, while 2 designates an electric motor having the armature shaft thereof connected with the pump 1 so that the latter will be operated when the motor is 60 energized.

3 designates a tank or reservoir capable of holding a quantity of water and leading from the discharge port of the pump 1 is a conduit 4 connected with the tank 3 so that 65 the water may be forced into the tank in the operation of the pump. The motor 2 is connected in an electric circuit 5 including a suitable source of electrical energy and located in the circuit 5 is a double pole single 70 throw switch 6. Connected with the blades of the switch 6 and insulated therefrom is a stem 7 secured to a core 8 adapted to work within a solenoid 9. Disposed within the tank 3 and adapted to rise and fall with the 75 water therein is a float 10 and secured to the float 10 and projecting upwardly therefrom through the upper end of the tank is a rod 11, while disposed parallel to the rod 11 and 80 uprising from the float is a relatively short 80 rod 12 adapted to project through an opening in the upper end of the tank when the float is moved upwardly under the action of the water. Mounted upon the upper end of the reservoir or tank 3 is a circuit closer 85 comprising, in the present instance, a stationary contact jaw 13 and a blade 14 pivoted at one end upon a bracket 15 and adapted to be moved into and out of engagement with the jaw 13. 90

16 designates a coiled expansion spring interposed between the lower end of the blade 14 and the top wall of the tank and this spring acts to hold the blade normally out of engagement with the contact jaw 13. The 95 blade 14, adjacent to the free end thereof, is formed with an opening and through this opening is passed the upper end of the rod 11 and such end of the rod is bent at an angle to itself as at 17 so that as the float approaches the bottom wall of the tank, incident to the level of the water in the tank falling, the blade 14 will be swung against the action of the spring 16 into engagement with the contact jaw 13. Appropriately 100 fastened to the top of the tank 3 adjacent to the circuit closer is a latching device. In this instance, the latching device comprises an electro-magnet 17' and an armature lever 18 pivoted at one end as at 19 and having the 110

opposite end adapted to engage the free end of the blade 14 to hold the blade in circuit closing position against the action of the spring 16. A retractile spring 20 has one 5 end secured to the armature lever 18 and the opposite end fastened to a suitable bracket secured to the top of the tank, the spring 20 serving to elevate the armature lever 18 when the magnet 17 is deenergized. The 10 circuit closer composed of the bracket 15, lever 14 and contact jaw 13, the electromagnet 17, and the solenoid 9, are connected in series with one another in an electric circuit 21 including a suitable source of energy 15 as a battery 22.

In practice, when the water level in the reservoir 3 falls, the float 10 moves downwardly and as the float nears the bottom of the tank, the end 17 of the rod 11 engages 20 the blade 14 and closes the circuit 21, thereby energizing the magnet 17 and the solenoid 9. When the solenoid 9 is energized, the core 8 is drawn into the same and in the 25 inward movement of the core the blades of the switch 6 are swung to circuit closing position, thereby closing the circuit of the motor 2 so that the pump may be operated. The pump delivers the water to the tank 3 and as the water enters the tank the float 10 30 rises so that the bent end of the rod 11 is disengaged from the blade 14. The blade 14, however, is held against movement to circuit closing position by the armature lever 18 and the magnet 17. As the float nears 35 the limit of its upward movement, the upper end of the relatively short rod 12 passes through the corresponding opening in the top wall of the tank and swings the lever 14 upwardly against the action of the magnet 17, thereby breaking the circuit 21 and deenergizing the solenoid 9 and the magnet 17. The blades of the switch 6 are preferably 40 connected with a spring 23 and the spring 23 reacts when the solenoid 9 is deenergized to open the circuit 5 of the motor. 45

While I have herein shown and described one preferred form of my invention by way of illustration, I wish it to be understood that I do not limit or confine myself to the 50 precise details of construction herein described and delineated, as modification and variation may be made within the scope of the claims without departing from the spirit of the invention.

If desired, the blade 14 may be pivoted 55 between its ends, as illustrated in Fig. 3, and the outer end formed with an opening to receive the rod 11 so that in the downward movement of the rod 11 the controlled circuit will be opened and in the upward move-

ment of the rod 12 the controlled circuit will be closed. This construction will be found especially useful on boats and the like when it is desired to set the pumps in operation after the water in the ship has risen above a 65 predetermined level, in the event of leakage or other causes.

I claim:

1. A float actuated circuit closer comprising an electroresponsive device for closing 70 said switch, a circuit closer, an electroresponsive latching device for holding said circuit closer in circuit closing position, an electric circuit including said solenoid circuit closer and latching device in series, means 75 holding said circuit closer normally in open position, a float, a rod connected to said float for actuating said circuit closer to closed position in one movement of the float, and a second rod connected to said float and operable therefrom to actuate the circuit closer to open position in the reverse movement of the float.

2. A float actuated circuit closer comprising an electroresponsive device connected to 80 said switch for actuating the latter to closed position, a circuit closer, a latching device comprising a magnet, and an armature lever under the control of said magnet and operable therefrom to hold said circuit closer 85 in circuit closing position, an electric circuit including said solenoid, circuit closer and magnet in series, a float actuated rod for actuating said circuit closer to closed position, and a second float actuated rod for moving 90 said circuit closer to open position against the action of said latching device.

3. A float actuated circuit closer comprising an electroresponsive device connected to 95 said switch for actuating the latter to closed position, a circuit closer, a latching device comprising a magnet, and an armature lever under the control of said magnet and operable therefrom to hold said circuit closer in circuit closing position, an electric circuit 100 including said solenoid, circuit closer and magnet in series, a float actuated rod for actuating said circuit closer to closed position, a second float actuated rod for moving said circuit closer to open position against the 105 action of said latching device, and a spring for holding said circuit closer normally in open position.

In testimony whereof I affix my signature in presence of two witnesses.

HOWARD PLYMALE.
